UNITED STATES PATENT OFFICE.

OLIVER C. MADISON, OF OMAHA, NEBRASKA; MINNIE B. MADISON EXECUTRIX OF
SAID OLIVER C. MADISON, DECEASED.

TOY PISTOL.

Application filed November 25, 1921. Serial No. 517,805.

To all whom it may concern:

Be it known that I, OLIVER C. MADISON, a citizen of the United States, residing at Omaha, in the county of Douglas and State of Nebraska, have invented certain new and useful Improvements in a Toy Pistol, of which the following is a specification.

This invention relates to a toy pistol, and has for its object to provide a device for 10 tossing or projecting a rubber ball or similar object for purposes of amusement, to be of such simple construction that it may be manufactured at a nominal cost and will be durable and effective for the purposes designed, and will be convenient in use. The 15 invention includes a single wire strand bent to provide the required parts, and consists of the novel construction, combination and arrangement of parts as described herein and claimed, and as illustrated in the accompanying drawing, wherein,—Fig. 1 is a side view of a toy pistol embodying the invention, the projector arm being in engagement with the trigger arm. Fig. 2 is a plan 20 view of the device. Fig. 3 is a view in side elevation of the toy pistol, the resilient arms being retracted.

Referring more particularly to the drawing, the invention consists of a single resilient strand or wire bent intermediate its ends to provide a loop or spring 4, a spring-arm 5 having an object-holder 6, preferably of circular form, at its terminal, and to provide a supporting-arm 7, said arm 7 and the 35 remaining part of the strand being bent to an angular form as indicated at 8, 9 and 10, the parts 8 and 9, respectively forming a side and bottom of a stock or handle, and the part 10 operating as a trigger and also 40 forming a part of the stock, said trigger or arm 10, at its junction with the lower end of the stock or part 9 being bent to a loop-form, as indicated at a to add to the resiliency of the trigger. The trigger 10 is also 45 bent outwardly as indicated at b to form a lug for engaging the loop 6, and is bent outwardly as indicated at c, adjacent to the lug b, to form a hand hold or guard; and at d is indicated a finger hold which is formed 50 by bending the strand inwardly at the junction of the parts 7 and 8, opposite to the outward curvature or hand hold c.

It will be understood that the parts depend upon resiliency for operation. The 55 projector-arm 5 with reference to the spring,

is normally disposed divergent from the supporting-arm, and may be swung downwardly against the force of the spring 4 to permit the loop 6 to be engaged by the lug b, the arm or trigger 10 being swung inwardly to a limited extent against the force of the spring a for this purpose, the lug b operating to normally maintain the parts as shown in Fig. 1.

A ball 11 or other object to be projected 60 is then placed upon or partly within the loop 6. The stock is then held in the hand of the operator, who, by manual compression, while aiming the pistol, may cause the trigger 10 to swing inwardly, which permits the loop 6 to be disengaged from the lug for projecting the ball.

While the curvatures c and d mentioned could be dispensed with, their use is preferred, the curvature d being for engagement of a finger of the operator when the parts are manually compressed, the curvature c tending to maintain the hand of the operator somewhat remote from the lug b. At e is indicated an angular part of the 75 projecting-arm, 5, adjacent to the holder-loop 6, said arm 5 being bent upwardly in a direction of said loop, whereby the loop will be disposed somewhat above the arm 5, the result being that the holder-loop 6 will 80 have a greater elevation at the time of its release from the lug b, and its arc of movement will be somewhat less than it would be if disposed in the plane of the arm 5.

It will be appreciated that, since the device may be constructed of a single piece of wire, bent to the form mentioned, it may be manufactured at a very limited expense, and that on account of the form and arrangement of parts it will be convenient in 90 operation.

What I claim as my invention and desire to secure by Letters Patent is,—

In a toy pistol, a resilient strand bent between its ends to provide a coiled spring 100 and a rectilinear projector arm having a circular loop at one terminal of the strand to form a holder for a ball, and forming a rectilinear supporting arm, and bent adjacent to and intermediate said supporting 105 arm and its second terminal to approximately an angular form to provide a handle having an inwardly curved part adjacent to the supporting arm for use as a finger-hold and having an outwardly curved 110

part adjacent to its second terminal to provide a hand-guard, said strand at its second terminal being provided with a lug adapted to engage within said loop, that part of the projector arm adjacent to the loop being bent outwardly to dispose the loop in a plane outwardly of the plane of the projector arm for limiting the arc of movement

of the loop when the lug is released from said loop.

In testimony whereof, I have affixed my signature in presence of two witnesses.

OLIVER C. MADISON.
